CONTAINER FILLING MACHINE

Everett S. Minard, Laguna Beach, Calif., assignor, by
mesne assignments, to Chemetron Corporation, a cor-
poration of Delaware

Application January 16, 1956, Serial No. 559,229

17 Claims. (Cl. 141—146)

This invention relates to receptacle filling machines and more particularly to apparatus for automatically filling serially presented portable receptacles with fluent materials.

The invention is especially concerned with a novel base assembly for holding various sub-assemblies. When the sub-assemblies are attached to the base assembly, different types of machines are obtained which are adapted to perform various types of filling operations dependent upon the properties of the fluent materials being filled into the receptacles.

Containers of metal, glass or plastics are widely used for the marketing of various types of fluid such as juices and beverages as well as mixtures of fluids and solids, such as soups, which are sealed into cans and bottles for sale at grocery stores and super-markets. As another example, different types of lubricants and oils have been made available at service stations for use in automobiles. New fluent materials are constantly being made available for sale in containers such as cans and bottles.

Because of the widespread sale and use of fluids and semi-solids in containers such as cans and bottles, the filling of the containers with such materials has become a large business. Since large numbers of containers such as cans and bottles have to be filled daily, many types of machines have been built which have made the filling operations highly automatic.

One of the problems in the filling machines now in use results from the different types of products which have to be filled into the containers at different times. For example, as the agricultural season progresses from the spring through the summer and into the fall, fluids having different viscosities may have to be filled into the cans. At one time a somewhat viscous fluid such as honey may have to be filled and at a different time during the growing season a somewhat non-viscous fluid such as apple juice may have to be filled into the cans. During the time that viscous material such as honey is being filled into the containers, one type of filling machine is used. Another type of filling machine is used when non-viscous fluids such as apple juice are being filled into the containers. This has required considerable expenditures of money for different equipment for different products. It has also required increased floor space for holding the different types of machines and increased maintenance charges for maintaining the machines even while they are idle.

This invention provides apparatus for overcoming the above disadvantages. The invention includes a base assembly which is adapted to hold different types of sub-assemblies. These sub-assemblies are adapted to perform filling operations with fluids of different viscosity when they are attached to the base assembly. For example, when viscous fluids are to be filled into cans, certain sub-assemblies can be attached to the base assembly to produce a machine having the desired properties. These sub-assemblies can be removed from the base assembly at the end of the filling operation and stored

2

until the next time that viscous fluids have to be filled. At the time that non-viscous fluids have to be filled, certain other sub-assemblies can be attached to the base assembly to produce a machine for filling the non-viscous fluids into containers such as cans and bottles. By using a single base assembly and attaching different sub-assemblies to the base assembly for obtaining the filling of different fluids, the amount of floor space required can be minimized. Furthermore, problems of maintenance and of expenditures for capital equipment also tend to become minimized.

The apparatus constituting this invention also includes certain components of novel structure. For example, novel types of valve assemblies are included in certain of the sub-assemblies. The valve stems in these assemblies are provided with spool portions having novel configurations in filling operations to obtain the filling of fluent material such as fluid into containers without the creation of any turbulence or air pockets in the fluid. The valve stem assemblies are also advantageous in that they can be easily withdrawn and cleaned to remove undesirable material which may have become stuck to the peripheries of the spool portions. In the drawings:

Figure 24 is an enlarged fragmentary view, partly in section, of certain valve members shown at the right of Figure 21 as seen from a position corresponding to that shown in Figure 21 and illustrates the relative disposition of these members at the same instant of operation as the corresponding members shown in Figure 23;

Figure 25 is an enlarged sectional view substantially on the lines 25—25 of Figures 21 and 26; and

Figure 26 is an enlarged fragmentary sectional view substantially on the line 26—26 of Figure 25.

Base assembly

Figures 1 and 2 show the base assembly upon which different sub-assemblies may be mounted to fill containers such as cans or bottles with fluent material by various types of operations. The containers can be filled by various types of operations such as by gravity, by

the use of pistons with the fluid being made available from a position above the cans or by the use of pistons with the fluid being made available from a position within the cans. The base assembly shown in Figures 1 and 2 includes an annular casing 10 which is open at its top end. The casing 10 is secured at its bottom end as by bolts 12 to a plurality of spaced pedestals 14 having tapped sockets. The pedestals 14 are disposed at spaced positions around the periphery of the casing 10 to provide a firm support for the casing.

Legs 16 are provided with threaded portions at their upper ends so that the legs can be screwed into the tapped sockets of the pedestals 14. The legs 16 are provided with flanges at their lower ends to obtain an attachment of the legs to floors as by bolts 22. The positioning of the pedestals 14 and the casing 10 above the floor can be adjusted by varying the dispositions of the legs 16 in the tapped sockets of their associated pedestals 14.

An annular housing 24 is provided with a substantially cylindrical portion and with an annular flange portion 26 extending outwardly from the bottom of the cylindrical portion. The cylindrical portion of the housing 24 has a tapped hole for receiving a plug 28 such that lubricant can be inserted into the housing when the set screw is removed. The flange portion 26 of the housing 24 is secured as by screws 30 to a lip portion extending inwardly from the top of the casing 10. The flange portion 26 is provided at its outer periphery with a plurality of bosses 32 spaced from one another at positions corresponding to the positions of the pedestals 14. The upper surfaces of the bosses 32 are milled to a high degree of smoothness for reasons which will be described in detail subsequently.

A shaft 34 is supported within the housing 24 at a pair of spaced positions and is disposed in rotatable relationship with respect to the housing as by bearings 36. The shaft extends downwardly through the housing 24 to a position within the casing 10 and carries a bevel gear 38 on the portion of the shaft within the casing. The bevel gear 38 is fixedly mounted on the shaft 34 as by a key and set screw 39. An annular support member 40 is fixedly positioned as by a key and set screw 41 on the shaft 34 at the upper end of the shaft. The support member 40 is positioned above the top of the housing 24. A seal 46 is provided between the housing 24 and the support member 40.

Certain horizontal surfaces are provided on the support member 40 for purposes of holding other members. A flat surface 50 is provided on an annular rim portion 52 at the bottom of the support member 40 and is milled to a high degree of smoothness. Tapped holes 54 extend axially into the rim portion 52 at spaced intervals along the rim portion to hold members which will be described in detail subsequently. In like manner, a flat surface 56 is formed on an annular shoulder portion 58 at an intermediate position on the support member 40 in the axial direction. The surface 56 is milled to a high degree of smoothness. Tapped holes 60 extend axially into the shoulder portion 58 at spaced positions along the shoulder portion to hold members which will be described in detail subsequently.

A bevel gear 60 is in mesh with the bevel gear 38 at a position within the casing 10 and is mounted as by a key and set screw 62 on a drive shaft 64. A bevel gear 66 is also fixedly carried on the shaft 64 at a position within an annular casing 68 which is open at the top end. The shaft 64 is supported at a pair of spaced positions within the casing 68 and is rotatable relative to the casing within bearing sleeves 70 supported by the casing. The casing 68 is fixedly suspended from the casing 10 as by screws 72 (Figure 2).

A housing 78 and a cover plate 80 are attached as by screws 82 to a lip portion at the top of the casing 68. The plate 80 covers the top of the casing 68 and the bot-

tom of the housing 78. The housing 78 is provided at its upper end with a flange portion 86 having an annular configuration. The upper face of the flange portion 86 is flat and is milled to a high degree of smoothness for reasons which will be described in detail subsequently. Tapped holes 88 extend into the flange portion 86 to receive screws for supporting other members which will be described in detail subsequently.

A shaft 90 is journaled into the cover plate 80 and the housing 78 at the upper end of the support member. The shaft 90 is rotatable within bearing sleeves 92 supported by the cover plate 80 and the housing 78. The shaft extends into the casing 68 at its lower end and carries at a position within the casing a bevel gear 94 which is in mesh with the bevel gear 66 so that shaft 90 is rotated oppositely with respect to shaft 34. The bevel gear 94 is fixedly positioned on the shaft 90 as by a key and set screw 95. At a position above the housing 78, the shaft 90 carries a sleeve 96. The sleeve 96 is fixedly positioned on the shaft 90 as by a key and set screw 97. The sleeve 96 flares outwardly at its upper end to form a flat surface 98 which is milled to a high degree of smoothness. Tapped holes 99 extend into the sleeve 96 to receive screws for holding other members which will be described in detail.

As the shaft 64 rotates, it drives the bevel gear 60 fixedly mounted on the shaft. Since the bevel gear 60 is in mesh with the bevel gear 38, it drives the bevel gear 38 so as to produce a rotation of the shaft 34. The shaft 34 in turn drives the support member 40 with respect to the housing 24. As will be described in detail subsequently, certain members are mounted on the support member 40. These members include conveyor apparatus for receiving containers such as cans to be filled and for moving the containers to an output station. The members also include a reservoir such as a tank for holding fluid and a plurality of valves for controlling the transfer of the fluid to the containers during the movement of the containers from the input station to the output station.

In addition to driving the bevel gear 60, the shaft 64 drives the bevel gear 66. Since the bevel gear 66 is in mesh with the gear 94, it drives the gear 94 so as to produce a rotation of the shaft 90. The shaft 90 in turn drives the sleeve 96. By disposing conveyor apparatus on the sleeve 96, the containers to be filled are able to be moved from an input station to a position for transfer to the conveyor apparatus mounted on the support member 40. The containers are moved along a platform mounted on the flange portion 86 of the housing 78.

Piston type of filling operation from a top-fill position

Figures 3 to 15, inclusive, show apparatus for filling containers with fluid by the depression of pistons, the filling operations being performed from a position above the containers. The filling apparatus shown in Figures 3 to 15, inclusive, is adapted to be mounted easily on the base assembly shown in Figures 1 and 2 and described fully above. As described previously, the base assembly includes the casings 10 and 68, the housings 24 and 78 and the various members supported by these structures.

The filling apparatus shown in Figures 3 to 15, inclusive, includes an annular bracket 100 (Figure 3) having a bottom flange portion which is supported as by screws 102 on the flat surface 56 of the shoulder portion 58 in the support member 40. The bracket 100 also has a top flange portion which supports an annular reservoir 104 such as a tank as by screws 106. The reservoir 104 is adapted to hold a fluent material indicated at 107 in Figure 3 such that the material is able to be directed into cans. The fluent material may be a fluid or a mixture of solid pieces and a fluid.

The bottom of the reservoir 104 slopes downwardly

5 at a relatively shallow incline toward the periphery of the container. A plurality of ports 108 (Figures 3, 6 and 7) are provided in the bottom of the reservoir 104 at spaced positions near the periphery of the reservoir. Bushings 109 are disposed within the ports 108 to receive spool portions of valve stems generally indicated at 110. The valve stems 110 are included in valves which will be described in detail subsequently. An annular top plate 112 having an open central portion is supported at the top of the reservoir 104 as by welding. Orifices 114 (best seen in Figure 10) are provided in the plate 112 at positions directly above the ports 108. Bushings 116 fit in the orifice 114 to guide the movements of the valve stems 110 which have a sliding fit therein.

10 A plurality of retainers 118 are suitably supported by the reservoir 104 (Figures 3, 6 and 7) at positions below the reservoir and in sealed relationship to the reservoir. The retainers 118 have concave configurations to form compartments 120 with the bottom of the reservoir 104 for holding fluid introduced to the chambers from the reservoir. Each of the retainers 118 is positioned below a different one of the ports 108 and is itself provided with a port 122 at a position directly below the associated port 108. Bushings 124 fit into the ports 122 to receive spool portions of the valve stems 110 in a manner similar to the bushings 109 in the ports 108. The bushings 124 are provided with an inner diameter slightly less than the inner diameter of the bushings 109 and are illustrated as interiorly bevelled at their upper end as at 125.

15 The retainers 118 are open at their upper ends and are so shaped at their upper ends as to be separated from the reservoir 104. The compartments 120 formed between the reservoir 104 and the retainer 118 communicate with the open lower ends of cylinders 126, which are suitably supported on the retainers 118. A slot 128 extends downwardly in each of the cylinders 126 from the upper edge of the cylinder to a position intermediate the upper and lower edges of the cylinder.

20 Stanchions 130 (Figures 3 and 5) are attached as by the bolts 31 to the bosses 32, which extend upwardly from the flange portion 26 of the housing 24 in a manner similar to that described above. Uprights 132 in turn extend vertically from reinforced portions 133 at upper peripheral positions in the stanchions 130. The uprights 132 in turn support an annular ring 134 at an intermediate position along their vertical length.

25 A support member 136 (Figure 3) is fixedly positioned above the ring 134 as by spacers 138 and studs 140 extending through the support members, the spacers and the ring. The support member 136 in turn holds in fixed positioning a track generally indicated at 142 (Figures 3, 4, 6, 7 and 12). The track 142 surrounds the reservoir 104 and includes a guide member 144 (best seen in Figure 12) lying adjacent to the cylinders 126. As shown in Figure 12, the guide member 144 rises in a shallow incline through almost half of its length and descends at a corresponding angle through almost the other half of its length. Between the rising and declining portions of the guide member 144 is a horizontal portion of relatively short length, as indicated at 145 in Figure 12.

30 The guide member 144 does not extend through an annular path of substantially 360 degrees but has its opposite ends separated by a moderate distance at a position near the top of its travel path. The opposite ends of the guide member 144 are joined by a bar 146 suitably attached as by welds to lateral positions on the opposite ends of the guide member 144. A stud 148 (best seen in Figure 15) extends through the bar 146 and through a spacer 150 suitably attached as by a weld to an annular collar 152. The collar 152 has a tapped hole extending in an axial direction to receive a threaded portion on the stud 148 near the head of the stud. The stud 148 and the collar 152 respectively have winged portions 154 and 155 (best seen in Figures 13 and 15) to facilitate

manual gripping. A bushing 156 is positioned between the collar 152 and the head of the stud 148.

In addition to the members described in the previous paragraph, the stud 148 carries an eccentric cam 160 at the end of its shank. The eccentric cam 160 is fixedly positioned on the stud 148 as by a pin 162 (Figure 15). The pin 162 extends into the shank portion of the stud 148 and has a collar which presses against the cam 160 to prevent rotary movements of the cam relative to the stud. The cam 160 is positioned below a runner 164 and is in engagement with the runner to control the pivotal disposition of the runner relative to a pin 166. The pin 166 extends through the bar 146 and screws into a socket in the runner 164.

At one end, the runner 164 (Figures 13 and 14) has a finger 168 which extends into a recess in the guide member 144 to provide a continuity with the guide member for the movement of control means such as rollers 170 (Figures 3, 6, 7 and 12), as will be described in detail subsequently. The finger 168 forms an extension on the runner 164 of a first portion which is inclined at a shallow angle relative to a horizontal plane. The runner 164 also has a second portion extending in a substantially horizontal direction and a third portion sloped downwardly at a steeper angle than the inclination of the first portion. A finger 172 (Figures 13 and 14) extends from the third portion of the runner 164 into a recess in the guide member 144 to provide a continuity for the movement of the rollers moving on the track 142.

A guide track 174 (Figure 12) is suitably supported by the ring 134 at a position directly above the track 142. The exact manner in which the guide track 174 is supported by the ring 134 is not shown in the drawings but a suitable arrangement can be made by a person skilled in the art. The guide track 174 has an annular configuration and has an angular length of approximately 180 degrees. The guide track 174 is substantially parallel to the guide member 144 of the track 142 along the declining portion of the guide member. At its upper end, the guide track 174 is inclined for a relatively short distance at a steeper angle than the inclination of the remaining portion of the track so that the track will guide the rollers 170 with optimum efficiency for a positioning of the rollers on the guide members 144. The guide track 174 is separated from the guide member 144 by a distance slightly greater than the diameter of the rollers 170 in order to obtain a free movement of the rollers on the guide member.

Brackets 178 (Figure 3) are carried by the uprights 132 at the upper end of the uprights and in fixed positioning on the uprights. The brackets 178 extend inwardly from the uprights 132 and in turn carry extension arms 180 at their inner ends as by screws 182. A guide track 184 is disposed at the inner end of the extension arms 180 at a position almost directly above the side wall of the reservoir 104. As may be best seen in Figures 3 and 12, the guide track 184 is disposed in substantially a horizontal plane along most of its angular length. The horizontal portion of the guide track 184 is positioned above the declining and horizontal portions of the guide member 144 and above the portion of the guide member at which the inclination starts to occur. The guide track 184 has a portion 186 (Figure 12) which rises at a relatively steep angle from a position below the horizontal portion of the track and which meets the horizontal portion of the track at the beginning of the horizontal portion in the direction of movement of the various members.

A guideway 188 (best seen in Figure 12) is suitably supported by the extension arms 180 (Figure 3) at a position adjacent to the end of the track 184 opposite from the inclined portion 186. The guide way 188 has a first horizontal portion disposed above the track 184 by a distance slightly greater than the diameters of control means such as rollers 190 adapted to ride on the guide

track. The guide way 188 also has a second portion which extends downwardly from the horizontal portion at a relatively sharp angle. The second portion of the guide way 188 extends downwardly to a position below the guide track 184 for reasons which will be described in detail subsequently. The second portion of the guide way 188 is separated from the end of the guide track 184 by a distance slightly greater than the diameter of the rollers 190.

The rollers 190 are positioned at spaced intervals corresponding to the orifices 114 (best seen in Figure 10) in the top plate 112 and are provided with annular peripheries for rolling movements on the guide track 184. The rollers 190 are loosely carried on pins 192 (Figures 9 and 10) which have threaded portions for screwing into tapped holes at one end of drive rods 194. At their other end, the drive rods 194 are pivotably attached to brackets 196 as by pins 198, each of which has a threaded portion for screwing into a tapped hole in its associated bracket. The brackets 196 are in turn attached to the top plate 112 as by studs 200 (Figure 9).

At an intermediate position along its length, each drive rod 194 has a slot 202 (Figures 10 and 11). A first portion of each slot 202 extends downwardly in a direction approaching the vertical and a second portion of each slot 202 extends toward the adjacent bracket 196 in a direction approaching the horizontal. The horizontal portion of each slot 202 receives a guide pin 204 which extends horizontally outwardly from an annular guide portion 206 at the top of the valve stem 110.

A spindle portion 210 extends downwardly from the guide portion 206 of each valve stem 110. At its bottom end, each valve stem 110 has an annular spool portion 212 (best seen in Figures 6 and 7) with a diameter for obtaining a snug fit of the spool portion within a different bushing 109 at the bottom of the reservoir 104. The spool portion 212 of each valve stem 110 is inclined at its upper and lower ends at a moderate angle with respect to a horizontal direction to provide a gradual closure of the associated parts 109 and 124. At its upper end, the spool portion 212 of each valve stem 110 is provided with a pair of spaced notches 214 (Figures 7 and 8) to further prevent an instantaneous closure of its associated port 103 upon an upward movement of the piston.

Just as the rollers 190 are provided with annular configurations to roll along the guide track 184, the rollers 170 are provided with annular configurations to roll along the guide member 144 and the runner 164. The rollers 170 are carried on pins 216 (best seen in Figure 6) for rotary movement relative to the pins. The pins 216 extend through the rollers 170 and guide bars 218 into pistons 220 for fixed positioning in the pistons as by set screws 222. The pistons 220 fit snugly within the cylinders 126 and move upwardly or downwardly in the cylinders in accordance with the movements of the rollers 170 on the guide member 144. The movements of the pistons 220 in the cylinders 126 in any direction other than the vertical direction are limited by disposing the bars 218 in the slots 128 in the cylinders.

At its upper end at an interior position, each of the stanchions 130 has a flat table portion 226 (Figure 3) for supporting a platform 228 in a substantially horizontal plane. The platform 228 is also supported on the upper surface of the housing 78 as by studs 230 so as to form an extension of the horizontal plane produced by the disposition of the platform on the table portions 226 of the stanchions 130. The platform 228 is adapted to support containers 232 for movement on the platform in a path which will be described in detail subsequently.

An annular support plate 234 is mounted as by studs 236 on the flat surface 50 of the rim portion 52 at the bottom of the support member 40. The support plate 234 in turn carries a substantially annular feed star 238 at its periphery as by studs 240. The feed star 238 is positioned at an intermediate distance along the height

of the containers 232 and at a position contiguous to the containers. As best seen in Figure 5, the feed star 238 has a plurality of pockets 242 at spaced intervals along its periphery. Each of the pockets 242 in the feed star 238 has a depth corresponding substantially to the diameter of the containers 232. Each of the pockets 242 also has at an interior position a portion 244 with a semi-annular configuration corresponding to that of the containers 232 to obtain a snug fit of the containers in the pockets. Each of the pockets 242 also has a widened mouth portion to facilitate the movement of the containers 232 into and out of the pocket.

The feed star 238 cooperates with an annular feed star 246 (Figures 3 and 5) to control the movements of the containers 232 along the platform 228. The feed star 246 is mounted on the flat surface 98 of the sleeve 96 as by studs 247 extending through the plate into the tapped holes in the sleeve. The feed star 246 is provided with pockets 248 (best seen in Figure 5) at its periphery at spaced intervals corresponding to the separation between the pockets 242 in the feed star 238. The pockets 248 are provided with substantially semi-annular configurations corresponding to those previously described in detail for the pockets 242.

Guide rails 250 and 252 (Figures 3 and 5) are attached to the platform 228 as by brackets 253. The guide rails 250 and 252 are positioned above the platform 228 at an intermediate distance along the height of the containers 232. The guide rail 250 extends forwardly along the platform 228 in a substantially linear direction as best seen in Figure 5. The guide rail 252 has a first portion which is substantially parallel to the rail 250 at a distance from the rail 250 corresponding substantially to the diameter of the containers 232. The guide rail 252 also has a second portion disposed in a semi-annular configuration at a distance from the interior of the pockets 248 in the feed star 246 corresponding substantially to the diameter of the containers 232.

A guide rail 254 (Figures 3 and 5) has a first portion which extends in an annular direction around the periphery of the feed star 238 from a position contiguous to the feed star 246. The first portion of the guide rail 254 is disposed in abutting relationship to the periphery of the feed star 238. The guid rail 254 also has a second portion which extends laterally along the platform 228 in a substantially linear direction at a forward position on the platform. The second portion of the guide rail 254 is substantially perpendicular to the guide rail 250. The guide rail 254 is attached to the platform 228 as by brackets 256.

A guide rail 258 is substantially parallel to the second portion of the guide rail 254 at a distance from the guide rail 254 corresponding to the diameter of the containers 232. An endless conveyor belt 260 normally forming a part of coupled equipment, such as machinery for closing the containers 232 extends along the platform 228 between the guide rails 254 and 258 to receive the containers 232 from the rotary plate 238 and to move the containers to such machinery. The conveyor belt 250 is illustrated as having upwardly protruding teeth 262 for engaging the containers 232 and for advancing the containers in properly spaced relationship to one another.

As the drive shaft 64 rotates, it drives the shaft 90 through the bevel gears 66 and 94 (Figure 3). Since the sleeve 96 is mounted on the shaft 90, it rotates with the shaft in a clockwise direction in Figure 5 and carries the feed star 246 with it. As the feed star 246 rotates, each of the pockets 248 in the feed star moves past the passageway formed between the guide rails 250 and 252 and receives one of the containers 232 from the passageway. The containers 232 are moved toward the feed star 246 along the passageway defined by the guide rails 250 and 252 by suitable apparatus (not shown). The containers rest on the platform 228 during this movement.

When the containers 232 become transferred into the

pockets 248 formed in the feed star 246, the containers move in a clockwise direction in Figure 5 in accordance with the movements of the feed star. The containers 232 are retained in fixed position within the pockets 248 of the feed star 246 because of the disposition of the guide rail 252 around the annular periphery of the feed plate. After the containers 232 have rotated with the feed star 246 through substantially one half of a revolution, the containers reach the feed star 238.

The feed star 238 rotates in a counterclockwise direction in Figure 5 at a speed synchronized with the rotary movements of the feed star 246 since it is driven by the shaft 64 through the bevel gears 60 and 38 (Figure 3). Because of the synchronization in the movements of the feed stars 238 and 246, the pockets 242 in the feed star 238 become aligned with successive pockets 248 in the feed star 246 at the position of contiguity between the feed stars. This may be best seen in Figure 5. By properly shaping the pockets 242 in the feed star 238 and the pockets 248 in the feed star 246, the containers 232 in the pockets 248 can become transferred to the pockets 242 for subsequent movement with the feed star 238.

Upon a transfer of the containers 232 to the pockets 242 in the feed star 238, the containers become fixedly positioned in the pockets because of the action of the guide rail 254 on the containers. This causes the containers 232 to follow the movements of the feed star 238 so that they subsequently reach the endless conveyor belt 260. The teeth 262 on the conveyor belt 260 then engage the containers 232 and carry the containers toward the output station (not specifically shown) in accordance with the movements of the belt. The containers are fixedly positioned on the belt 260 because of their engagement by the teeth 262 and because of their disposition between the guide rails 254 and 258.

During the movement of the containers 232 with the feed star 238, the containers become filled with the fluid 107 in the reservoir 104. This results from the operation of certain valve members as will be described in detail subsequently. The operation of one group of valve members is controlled by the movements of the rollers 190 on the guide track 184. As may be best seen in Figure 12 and as previously described in detail, the guide track 184 is positioned in a horizontal plane for an angular distance of approximately 180 degrees. The rollers 190 become positioned on the horizontal portion of the guide track 184 because of the operation of the inclined portion 186 of the track in directing the rollers upwardly to the horizontal portions of the rollers. At the end of their movement along the horizontal portion of the guide track 184, the rollers 190 are quickly guided to a position below the horizontal portion of the guide track. The rollers 190 move to a position below the horizontal portion of the guide track 184 since they are directed downwardly by the guideway 188.

As the rollers 190 move upwardly or downwardly, they carry the drive rods 194 (best seen in Figure 10) with them. This causes the drive rods 194 to pivot on the pins 198 (Figures 9, 10 and 11) as fulcrums such that the rods rise and fall at an intermediate position in accordance with the movements of the cams. Since the guide pins 204 extend into the slots 202 in the drive rods 194, the rods 194 drive the pins and the valve stems 110 from which the pins extend. Because of this coupled relationship, the valve stems 110 move upwardly and downwardly in accordance with the movements of the rollers 190 in the vertical direction.

When the valve stems 110 move downwardly into the position shown in Figure 7, the spool portions 212 at the bottom of the valve stems move into positions within the bushings 124 to seal the ports 122. By sealing the ports 122, any fluent material in the compartments 120 is prevented from passing through the ports into the containers 232 positioned below the ports. At the same

time that the ports 122 are sealed against the passage of fluent material, the ports 108 are opened for the passage of the fluent material into the compartments 120 and into the portions of the cylinder 126 below the pistons 220.

After the compartments 120 and the portions of the cylinders 126 below the pistons 220 have become filled with fluent material, the rollers 190 start to move upwardly along the inclined portion 186 of the guide track 184 in Figure 12. This causes the spool portions 212 of the valve stems 110 to move upwardly such that the ports 122 become opened for the flow of fluent material out of the ports. At the same time that the ports 122 become opened, the ports 108 become closed to prevent any further flow of fluent material from occurring from the reservoir 104 into the compartments 120. In this way, only a measured amount of the fluent material 107 from the compartment 106 is able to flow into each of the containers 232.

By providing the guide track 184 and the guideway 188 with proper configurations (best seen in Figure 12) and by properly shaping the spool portions 212 of the valve stems 110, the ports 108 and 122 become opened without any turbulence or spattering of the fluent material during the flow of the material. The inclined portion 186 of the guide track 184 and the guideway 188 are provided with the proper slopes to produce a movement of the rollers 190 into or out of sealing relationship with the ports 108 and 122 at the proper speeds. The notches 214 prevent simultaneous closure of ports 108 and 122.

The flow of fluent material into or out of the compartments 120 is facilitated by the action of the pistons 220 (best seen in Figures 6, 7 and 12). The movements of the pistons 220 are controlled by the movements of the rollers 170 along the guide member 144. As the rollers 170 roll upwardly along the inclined portion of the guide member 144 in Figure 12, they carry the pistons 220 upwardly because of the connections of the rollers to the pistons through the pins 216 in Figure 6. The movements of the rollers 170 along the guide member 144 can be converted into only vertical movements of the pistons 220 since the guide bars 218 (Figure 6) are positioned within the slots 128 in the piston cylinders 126 to limit the movements of the pistons in directions other than the vertical.

As will be best seen in Figure 12, the rollers 170 move upwardly along the guide member 144 during the time that the rollers 190 are in their depressed position. This causes the pistons 220 to move upwardly in the cylinders 126 at the time that the fluent material 107 is flowing into the compartments 120 from the reservoir 104. The gradual movement of the pistons 220 in an upward direction during this time helps to produce an even flow of fluent material into the compartments 120 so that air pockets cannot be created in the fluid. This is important in insuring that a proper amount of fluent material subsequently flows into each of the containers 232.

As previously described, the ports 108 become closed and the ports 122 become opened when the rollers 190 move upwardly along the inclined portion 186 of the guide track 184. This causes the fluent material 107 in the compartments 120 to flow into the containers 232 and prevents any further fluent material from flowing into the compartments from the reservoir 104. At the time that the fluent material in the compartments 120 starts to flow into the containers 232, the rollers 170 associated with the compartments start to move down the declining portion of the guide member 144. This may be best seen in Figure 12.

Since the pistons 220 follow the downward movement of the rollers 170, the pistons move downwardly as the fluent material in the compartment 120 flows into the containers 232. This causes the pistons 220 to exert a substantially constant pressure on the fluent material so

as to drive the fluent material at an even rate of flow into the containers 232. This tends to further minimize the creation of air pockets in the fluent material 107 as it flows into the containers 232. By synchronizing the downward movements of the pistons 220 with the opening of the ports 122, the pistons 220 are able to produce a flow into the containers 232 of heavy liquids and even of certain semi-solids and powdered solids or solids formed from fine or broken pieces of material.

The amount of fluent material flowing into the compartments 120 and into the portions of the cylinders 126 below the pistons 220 is dependent upon the stroke of the pistons. When the stroke of the pistons 220 in the cylinders 126 is increased, the space in the cylinders below the pistons becomes correspondingly increased at the end of the upward movements of the pistons. This causes an increased amount of fluent material to flow into the compartments 120 and into the portions of the cylinders 126 below the pistons 220. Upon a decrease in the stroke of the pistons 220, a corresponding decrease is obtained in the amount of fluent material flowing into the compartments 120 and into the portions of the cylinders 126 below the pistons.

The stroke of the pistons 220 can be controlled by the members shown in Figures 13 to 15, inclusive, and described fully above. The adjustment can be made by first loosening the collar 152 on the stud 148 and manually rotating the stud. The stud 148 can be easily rotated since the winged portion 154 can be gripped to apply a torque. The cam 160 rotates with the stud 148 as the stud is turned since the cam is fixedly positioned relative to the stud as by the screw 162.

Since the cam 160 is eccentric, it acts upon the runner 164 to produce a vertical movement of the runner at the right end of the runner in Figure 14. The runner 164 pivots on the pin 166 as the right end of the runner in Figure 14 moves in a vertical direction. This causes the height of the runner 164 above the adjacent portions of the guide member 144 to become correspondingly adjusted. After a proper adjustment in the height of the runner 164 has been made, the collar 152 is tightened on the stud 148 to lock the stud and the cam 160 in fixed position.

By producing a pivotal movement of the runner 164, the height of the runner above the adjacent portions of the guide member 144 can be adjusted without interrupting the continuity between the guide member and the runner. This is important in producing an uninterrupted movement of the rollers 170 as they move between the guide member 144 and the runner 164. The continuity in the movement of the rollers 170 is also obtained by providing the runner 164 with rising, horizontal and declining portions and by disposing the fingers 168 and 172 at the ends of the runner.

Various other members can be used to obtain simple and easy controls over the filling operation. For example, when relatively tall containers 232 are used, the bracket 100 (Figure 3) mounted on the rim portion 52 of the support member 40 may have an increased height so that the bottom of the reservoir 104 may clear the tops of the containers. In like manner, the bracket 100 may have a relatively short height when the containers 232 are relatively short.

Containers 232 of different volume can also be filled by adjusting the stroke of the pistons 220. The stroke of the pistons 220 may be adjusted by replacing the guide member 144 with another guide member having a different slope in its inclined and declining portions than the slope shown in Figure 12 for the member 144. By providing a guide member 144 with portions of different slopes than those shown in Figure 12, the pistons 220 move upwardly a different distance so that a different amount of fluent material can be moved into the space in the cylinders 126 below the pistons. In this way, containers having different volumes can be filled.

The containers 232 can be filled accurately to a desired level by adjusting the positioning of the eccentric cam 160. This causes the height of the runner 164 to become correspondingly varied and the stroke of the pistons 220 to become correspondingly adjusted. Since the stroke of the pistons 220 can be adjusted, the amount of fluent material flowing into the portion of the cylinders 126 below the pistons can be correspondingly varied. By this arrangement, the adjustment in the vertical height of the runner 164 provides a sensitive variation as to the amount of fluent material flowing into the containers 232.

Controls may also be provided by the support plate 234 (Figure 3) and the guide plate 238. For example, when a new filling operation is initiated with containers 232 of a different diameter than previously used, the support plate 234 and the feed star 238 may be easily replaced with a new support plate and a new guide plate to conform to the diameter of the new containers. The new support plate 234 and the new feed star 238 may be easily mounted on the support member 40 by first removing the studs 236 to remove the plate 234 and the feed star 238 previously being used and by subsequently inserting the studs after the new plate and feed star have been properly positioned for use.

The apparatus described above has certain other important advantages. These advantages include the construction of the valve stems 110 (Figures 6 and 7) and their associate valve members. By supporting each of the valve stems 110 at a pair of spaced positions such as at the guide portions 206 and the spool portions 212, a linear movement of the valve stems in a vertical direction is insured. This is important in obtaining proper opening and closing of the ports such as the ports 108 and 122 (best seen in Figure 6).

The valve stems 110 are also advantageous in that they wipe clean the annular surfaces of the bushings 109 in each stroke of the valve stems so that fluent material cannot solidify on the surfaces and jam the operation of the filling apparatus. The wiping action of the spool portions 212 is also important in preventing such material as sugar from caking on the surfaces of the bushings 109.

The configuration of the valve stems 110 is advantageous from another standpoint. As previously described, the guide portions 206 on the valve stems 110 have a slightly greater diameter than the spool portions 212. Because of this, the valve stems 110 can be easily lifted out of the reservoir 104. This is important when it is desired to clean the valve stems 110 in a minimum amount of time so that the filling operation will not be unduly interrupted.

The valve stems 110 can be easily detached from their coupled relationship to the drive rods 194 (Figures 9, 10 and 11) when it is desired to remove the pistons from their positioning within the reservoir 104. The valve stems 110 can be easily removed by lifting them in the slots 202 of the drive rods 194. The relationship of the valve stems 110 to the drive rods 194 in a partially removed disposition of the pistons can be seen in Figure 11.

The apparatus shown in Figures 3 to 15, inclusive, and described fully above is advantageous for another reason of considerable importance. This results from the fact that certain sub-assemblies can be easily attached to the base assembly shown in Figures 1 and 2 when a piston-type of filling operation from a position above the containers 232 is desired. For example, a first sub-assembly can include the bracket 100, the reservoir 104, the retainers 118, the piston cylinders 126, the valve stems, the pistons 220, the rollers 170 and 190, the support plate 234 and the feed star 238. A second sub-assembly can include the stanchions 130, the uprights 132, the ring 134, the track 142, the brackets 178, the extension arms 180 and the guide track 184.

The two sub-assemblies described in the previous paragraph can be stored until such time as a piston-fill type

of operation from a top-fill position is desired. The sub-assemblies can then be removed from storage and quickly secured to the base assembly shown in Figures 1 and 2 in the proper relationship of the various members described fully above. The first sub-assembly described in the previous paragraph can be quickly attached to the base assembly shown in Figures 1 and 2 by attaching the bracket 100 as by the screws 102 to the shoulder portion 58 of the support member 40. In like manner, the second sub-assembly described in the previous paragraph can be quickly attached to the base assembly shown in Figures 1 and 2 by attaching the stanchions 130 as by the screws 31 (Figure 1) to the bosses 32 on the flange portion 26 of the housing 24. After the filling operation has been completed, the sub-assemblies can be easily removed from the base assembly by removing the screws 31 and 102.

It should be appreciated that the containers 232 are filled on a sequential basis. This may be best seen in Figure 12, which shows all of the containers 232 moving angularly with the feed star 238 at one particular instant. For purposes of illustration, the compartments 120 are shown in Figure 12 as being filled from the second through seventh positions where the count of positions is made from the left. The filling of the containers 232 is shown in Figure 12 as occurring from the eighth through thirteenth positions where the count of positions is made from the left.

Piston type of filling operation from a bottom-fill position

The apparatus shown in Figures 16 to 20, inclusive, is adapted to fit on the base assembly shown in Figures 1 and 2 and described fully above so as to perform an operation known by persons skilled in the art as a piston type of filling operation from a position below the tops of the containers being filled. The filling apparatus shown in Figures 16 to 20, inclusive, is adapted to be mounted easily on the base assembly shown in Figures 1 and 2 and described fully above. As described previously, the base assembly includes the casings 10 and 66, the housings 24 and 78, the drive shaft 64 and the various members supported by these structures.

The filling apparatus shown in Figures 16 to 20, inclusive, includes an annular casing 300 mounted on the flat surface 50 of the rim portion 52 at the bottom of the support member 40. The casing 300 extends downwardly from the support member 40 to enclose the housing 24. At its bottom end, the casing 300 has a flange portion 302. Guide posts 304 (best seen in Figure 18) are supported in an upright position by the flange portion 302 of the casing 300 at spaced positions along the annular length of the flange portion. Lifters 306 are slidable on the posts 304. At a position near the bottom of the lifters 306, the lifters have lobe portions 308 which are provided with tapped holes to receive support pins 310. The pins 310 carry control means such as rollers 312 for rotary movement relative to the pins. The lifters 306 and the rollers 312 may be prevented from rotating on the posts 304 by apparatus similar to that shown in Figure 25. This apparatus may include tongue portions extending from the columns 306 and yoked at their outer ends to receive pins which extend upwardly from the casing 300.

At their upper ends, the lifters 306 have flange portions for suitably supporting pedestals 314 (best seen in Figures 18 and 19) as by bolts 316. Pins 318 (Figure 18) may be positioned in sockets in the pedestals 314 and in the flange portions of the lifters 306 to align the pedestals with the lifters. A feed star 320 is positioned above the pedestals 314 and is separated from the pedestals by spacers 322. The feed star 320 and the spacers 322 are attached to the pedestals 314 as by screws 324.

The feed star 320 is provided with pockets 326 (Figure 17) for holding containers 328. The pockets 326 are provided with annular configurations at their inner ends to receive the containers 328 snugly within the pockets.

The pockets 328 are also provided with cut-away portions at their peripheries so that the containers 328 can be easily transferred into the pockets for movement with the feed star 320.

A threaded support tube 330 (Figures 16 and 17) has a flange portion which is positioned on the shoulder 58 of the support member 40 and which is attached to the support member as by screws. A sleeve 332 having a tapped hole is adapted to be screwed on the threaded periphery of the support member 330. The sleeve 332 is slotted along its axial length and ears 334 are projected outwardly from the slotted ends of the sleeve. A bolt 336 (Figure 17) extends through holes in the ears 334 of the sleeve 332 to clamp the ears and maintain the sleeve in fixed position on the support tube 330.

At its upper end, the sleeve 332 is provided with an annular flange portion which supports the reservoir 104 for holding fluent material 337 (Figure 16) such as fluid. As previously described, the reservoir 104 is provided with the ports 108 at spaced positions in the bottom of the reservoir. The retainers 118 are supported by the reservoir 104 and are provided with the ports 122 in a manner similar to that described above. The cylinders 126 extend upwardly from the retainers 118 in a manner similar to that described above.

The ports 122 in the retainers 118 are tapped to receive threaded portions at the top of elongated sleeves 348. The sleeves 348 extend downwardly toward the cans 328 and have annular neck portions 350 at their lower ends. The portions of the sleeves 348 just above the neck portions 350 may be tapered for reasons which will be described in detail subsequently. The retainers 118 and the sleeves 348 cooperate to form compartments 344 (best seen in Figures 18 and 19).

Support bars 354 are attached as by bolts to the upper surfaces of the bosses 32 of the housing 24. The support bars 354 extend outwardly in a substantially horizontal direction from the bosses 32 of the housing 24 and hold stanchions 356 in fixed position at their outer end. The stanchions 356 extend upwardly from the support bars 354. At an intermediate position along their vertical length, the stanchions 356 support the annular ring 134 also shown in Figure 3. The track 142 and the various members forming the track are supported by the ring 134 in a manner similar to that described above. The guide track 184 and the guide way 188 are also included in the embodiment shown in Figures 16 to 20, inclusive.

The rollers 170 are adapted to roll along the track 144. The rollers 170 are suitably attached to the pistons 220 disposed in the piston cylinders 126. In like manner, the rollers 190 move on the track 184. The rollers 190 are coupled to valve stems 384 through members corresponding to those shown in Figures 9 to 11, inclusive, and described fully above so as to produce vertical movements of the valve stems in accordance with the vertical movements of the cams.

The valve stems 384 have a configuration through most of their lengths corresponding to the configurations of the valve stems 110 in the embodiment shown in Figures 3 to 15, inclusive. For example, spool portions 386 (best seen in Figures 18 and 19) corresponding to the spool portions 212 on the valve stems 110 are provided at positions near the bottoms of the valve stems 384. The spool portions 386 on the valve stems 384 are adapted to close the ports 108 in the reservoir 104 in one position of the valve stems. However, the spool portions 386 on the valve stems 384 are not adapted to close the ports 122 in the retainers 118 in any position of the valve stems. The valve stems 384 also have spindle portions 388 which extend downwardly from the spool portions 386 through a distance approximating the axial lengths of the sleeves 348. Spool portions 390 are provided near the bottom of the spindle portions 388 to close the neck portions 350 of the sleeve 348 in one position of the valve stems. The

spool portions have a diameter slightly less than the diameter of the spool portions 386 so that the valve stems can be easily lifted out of the reservoir 104. The bottom surfaces of the spool portions 390 may be tapered at an angle corresponding to the taper of the sleeve 348 just above the neck portion 350 so as to insure the full closure of the sleeve at the neck portion.

Brackets 392 (Figure 16) are mounted as by bolts on the support bars 354. The brackets 392 extend upwardly from the support bars 354 and hold at their upper end a guide track 394. The rollers 312 are adapted to roll on the guide track 394. As best seen in Figure 20, the guide track 394 has a first portion inclined at a relatively steep angle and a second portion sloping downwardly at a relatively shallow angle. The inclined portion of the guide track 394 is positioned almost directly below the inclined portion of the guide track 184. The downwardly sloping portion of the guide track 394 may terminate at a vertical level corresponding substantially to the initial position of the inclined portion on the guide track. The angular length of the guide track 394 may be slightly greater than 180 degrees.

The feed star 246 is mechanically coupled to the sleeve 96 in a manner similar to that described above to control the movements of the container on a platform 398. The feed star 246 rotates with the sleeve 96 and receives in its pockets the containers 328 being moved toward the feed star from the input station (not shown). The transfer of the containers 328 to the pockets in the feed star 246 is obtained in a manner similar to that shown in Figure 5 and described fully above. The feed star 246 then moves the containers 328 through approximately half of a revolution of the feed star to a position contiguous to the pedestals 314.

The feed star 320 rotates in synchronization with the feed star 246 since they are both driven through bevel gears from the main shaft 64. Because of this synchronization in the movements of the feed stars 320 and 246, the pockets 326 in the feed star 320 become aligned with the pockets in the feed star 246 as the feed stars rotate. By properly shaping the pockets 326 in the feed star 320, the containers 328 become transferred from the platform 398 to the pedestals 314 during the rotary movements of the guide plates 320 and 246.

As previously described, the pedestals 314 are mounted on lifters 306 (best seen in Figure 18), which are in turn slidable on the posts 304. The lifters 306 also carry the rollers 312, which are adapted to roll on the guide track 394 (Figures 16 and 20). Because of this relationship, the lifters 306 move upwardly along the posts 304 at a rapid rate as the rollers 312 reach the inclined portion of the guide track 394 (best seen in Figure 20). The lifters 306 then move downwardly along the posts 304 at a relatively slow rate as the rollers 312 move along the downwardly sloped portion of the guide track 394. The lifters 306 remain in their depressed position as the rollers 312 move angularly between the end of the downwardly sloped portion on the guide track 394 and the beginning of the upwardly sloped portion on the track. Since the pedestals 314 follow the movements of the lifters 306, the pedestals initially move upwardly at a rapid rate, then downwardly at a relatively slow rate and finally remain in a depressed position during each complete revolution of these members.

As may be best seen in Figure 20, the pedestals 314 remain in their depressed position during the time that the valve stems 384 are in their depressed positions. The valve stems 384 are in their depressed positions at these times since the valve stems are coupled to the rollers 190 and since the rollers are forced into a depressed position by the action of the guide track 188. Because of the disposition of the valve stems 384 in a depressed relationship, the spool portions 390 on the valve stems close the neck portions 350 at the bottom of the sleeves 348. This prevents any fluent material in the compartments

344 from passing through the sleeves 348 into the containers 328. The closure of the neck portions 350 on the sleeves 348 is insured because of the taper provided on the bottom of the spool portions and the corresponding taper on the portions of the spool portions above the neck portions 350.

At the same time that the neck portions 350 become closed by the disposition of the valve stems 384 in a depressed state, the ports 108 in the reservoir 104 become opened, as best seen in Figure 18. This causes the fluent material 337 in the reservoir 104 to start flowing through the ports 108 into the compartments 344 and into the space in the cylinders 126 below the pistons 220. As the fluent material 337 starts to flow, the rollers 170 start to roll upwardly along the inclined portion of the track 142 (best seen in Figure 20) so as to withdraw the pistons 220 upwardly in the cylinders 126. By moving the pistons 220 upwardly in the cylinders 126 as the fluent material starts to flow through the ports 108 in the reservoir 104, an even flow of fluent material into the compartments 344 is obtained to minimize turbulence and the creation of air pockets in the fluent material in the compartments.

The pistons 220 become withdrawn upwardly during the time that the pedestals 314 and the valve stems 384 remain depressed, as may be best seen in Figure 20. At substantially the end of the time that the pedestals 314 and the valve stems 384 remain depressed, the pistons 220 reach their topmost position in the cylinders 126. This causes a maximum amount of fluent material to be stored in the compartments 344 and in the space in the cylinders 126 below the pistons 220. The amount of fluent material stored in this space can be varied by adjusting the height of the runner 164 in a manner similar to that described above for the embodiment shown in Figures 3 to 15, inclusive.

After a maximum amount of fluent material has flowed from the reservoir 104 into the compartments 344, the rollers 190 start to move upwardly along the inclined portion of the guide track 184. This causes the valve stems 384 to move upwardly such that the ports 108 become closed (best seen in Figure 19) to prevent any further flow of the fluent material 337 from the reservoir 104 into the compartments 344. At the same time, the neck portions 350 in the sleeves 348 become opened for a flow of fluent material from the compartments 344 into the containers 328. It will be appreciated that the term "fluent material" includes material of any viscosity and also includes liquids holding solid particles or chunks.

At an instant before the fluent material 337 starts to flow from the compartments 344 into the containers 328, the pedestals 314 become raised by the movement of the rollers 312 along the inclined portion of the guide track 394 (best seen in Figure 20). Since the pedestals 314 become quickly raised to a maximum height, the containers 328 resting on the pedestals become raised to a position where the sleeves 348 protrude a considerable distance into the containers, as shown best in Figures 19 and 20. This causes the fluent material flowing through the neck portions 350 of the sleeves 348 to drop only a relatively small distance between the sleeves and the bottom of the containers 328. This tends to minimize spattering of the fluent material for the prevention of waste, especially when the material is a thin liquid. It also tends to minimize the creation of turbulence and of air pockets in the fluent material as the material flows into the containers 328. This is especially true of liquids which flow freely.

As the fluent material flows into the containers 328, the rollers 312 move downwardly along the declining portion of the guide track 394 (best seen in Figure 20). The rollers 312 in turn drive the pedestals 314 downwardly. Since the containers 328 move downwardly with

the pedestals 314, the containers become withdrawn from the sleeves 348 as the level of the fluent material rise in the containers. Because of this, the distance through which the fluent material 337 has to drop from the neck portions 350 of the sleeves 348 to the fluent material in the containers 328 remains substantially constant even with rises in the level of the fluent material in the containers.

During the flow of fluid from the reservoir 104 into the compartments 344, the rollers 170 roll downwardly along the declining portion of the guide member 144. Since the pistons 220 are coupled to the rollers 170, the pistons are forced downwardly by the rollers during the flow of the fluent material. In this way, the pistons 220 are positioned in the cylinders 126 at all times to press against the fluent material so as to insure a movement of the fluent material into the containers 328. This may be especially important when the fluent material is a heavy liquid or a solid formed from particles or pieces of material. For example, for such materials as sticky fluids and pastes which do not flow easily, the downward movement of the pistons 220 may be necessary to force the fluent material into the container 328.

It should be appreciated that the containers 328 are filled on a sequential basis. This may be best seen in Figure 20, which shows all of the containers 328 moving angularly with the feed star 320 at one particular instant. For purposes of illustration, the fluent material in the various containers 328 is illustrated by shaded areas formed from a plurality of dots. As will be seen in Figure 20, the four containers at the left in Figure 20 have been completely filled and are ready to be transferred to the output station as by an endless conveyor belt similar to the belt 260 in Figure 5.

The containers 328 transferred to the output station are replaced by new containers which are transferred to the pockets in feed star 320 (Figure 17) from the feed star 246 (Figure 16) when the feed stars have the proper disposition relative to each other, such as is shown at the right in Figure 16. The new containers 328 do not initially have any fluent material in them. This is illustrated by the seventh container in Figure 20 when the containers are counted from the left in that figure. The remaining containers 328 in Figure 20 have progressively increasing amounts of fluent material in them such that the container at the right in Figure 20 is almost full.

The apparatus described above is advantageous because it can be disposed in certain sub-assemblies which can be easily attached to or detached from the base assembly shown in Figures 1 and 2. For example, a first sub-assembly can include the casing 300, the posts 304, the lifters 306, the rollers 312, the support tube 330, the sleeve 332, the reservoir 104, the retainers 340, the cylinders 126, the rollers 170 and 190 and the valve stems 384. A second sub-assembly can include the support bars 354, the stanchions 356, the ring 134, the tracks 142 and 184, the brackets 392 and the guide track 394.

When it is desired to use the apparatus shown in Figures 16 to 20, inclusive, and described fully above, the first sub-assembly mentioned in the previous paragraph can be easily attached as by screws to the rim portion 52 of the support member 40. In like manner, the second sub-assembly mentioned in the previous paragraph can be easily attached as by screws to the bosses 32 on the flange portion 26 of the housing 24. After the filling operation has been completed, the first and second sub-assemblies can be easily detached from the base assembly shown in Figures 1 and 2 by removing the appropriate screws. The sub-assemblies can then be stored until the next time that a piston type of filling operation from a bottom-fill position is desired. After the sub-assemblies have been removed from the base assemblies, various other sub-assemblies can be attached to the base assemblies to obtain different types of filling operations.

It should be appreciated that the valve stems 384 have

the same advantages as the valve stems 110 in the embodiment shown in Figures 3 to 15, inclusive. The valve stems 384 are further advantageous in the provision of the spool portions 390 at the bottom of the valve stems. These spool portions are advantageous in insuring that the neck portions 350 of the sleeves 348 become fully closed against the leakage of fluent material out of the compartments 344 into the containers 328. Since the spool portions 390 have a slightly smaller diameter than the spool portions 386, the valve stems 384 are able to be withdrawn easily from the reservoir 104 so that they may be cleaned of foreign matter which may have accumulated on the valve stems.

It should also be appreciated that the apparatus shown in Figures 16 to 20, inclusive, does not necessarily have to be stored in the form of sub-assemblies. Actually, it may be desirable to retain loose parts or groups of parts and to build the apparatus from these parts. For example, it may be desired to store in disassembled relationship such parts as the cylinders 126, the pistons 220 and the tracks 142 and 184. The reason for this is that such parts can be used in the apparatus shown in Figures 3 to 15, inclusive, as well as in the apparatus shown in Figures 21 to 26, inclusive.

In like manner, it may be desired to store in disassembled relationship such parts as the posts 304, the lifters 306 and the pedestals 314. These parts can be stored loosely since they have use in the apparatus shown in Figures 21 to 26, inclusive, as well as in the apparatus shown in Figures 16 to 20, inclusive. By storing the various parts in their disassembled relationship, only a minimum number of parts is needed to build up apparatus for performing various types of filling operations. These types of filling operations can include those specifically discussed in this application and others not specifically discussed in this application. In this way, only a minimum amount of capital investment is needed to perform a wide variety of different filling operations.

Gravity type of filling operation

The apparatus shown in Figures 21 to 25, inclusive, is adapted to fit on the base assembly shown in Figures 1 and 2 and described fully above so as to perform a filling operation shown by persons skilled in the art as a gravity type of filling. The filling apparatus shown in Figures 21 to 25, inclusive, is adapted to be mounted easily on the base assembly shown in Figures 1 and 2 and described fully above. As described previously, the base assembly shown in Figures 1 and 2 includes the casings 10 and 66, the housings 24 and 78 and the various members supported by the various structures.

The filling apparatus shown in Figures 21 to 25, inclusive, includes the annular casing 300 mounted on the support member 40. The apparatus also includes the posts 304 and the lifters 306 slidable vertically on the posts. As described previously in connection with the embodiment shown in Figures 16 to 20, inclusive, the lifters 306 carry the control means such as the rollers 312 at intermediate positions in the vertical direction. The lifters 306 also carry at upper positions the pedestals 314 for supporting containers 420. The pedestals support the feed star 320 as well as the containers 420.

In addition to carrying the casing 300, the support member 40 also carries the sleeve 330 forming a part of the embodiment shown in Figures 16 to 20, inclusive. The sleeve 330 is threaded into the sleeve 332 and is secured therein by the bolt 336 in the manner described for the form shown in Figure 16.

At its upper end sleeve 332 is provided with an annular flange portion which supports a plate 424. A reservoir 426 in turn rests on the plate 424. The reservoir 426 may be provided with a construction and configuration somewhat similar to that described above for the container 100 in the embodiment shown in Figures 3 to 15, inclusive. Because of this, either the reservoir 104 or a dif-

ferent member may be used as the reservoir 426. Holes 428 (best seen in Figures 23 and 24) may be provided in the plate 424 and in the reservoir 426 at spaced intervals near the peripheries of these members. The holes 428 in the plate 424 may be chamfered as at 430 to receive lip portions provided around the peripheries of the holes in the container 426.

Tubes 434 (best seen in Figures 23 and 24) extend downwardly through the holes 428 in the plate 424 and the container 426. The tubes are provided at their upper end with outwardly flared rim portions 436. The rim portions 436 of the tubes 434 seat on the reservoir 426 at positions above the chamfered surfaces 430 of the holes 428 in the plate 424 so as to maintain the tubes in fixed positioning relative to the reservoir and the plate. The periphery of the tube 434 is threaded at a position near the top of the tube. At an intermediate position along their height, the tubes 434 are provided with shoulder portions 438. The tubes 434 are open at their upper and lower ends.

Retaining rings 440 (best seen in Figures 23 and 24) screw on the threaded portions of the tubes 434 to tighten the plate 424 and the container 426 against the rim portions 436 of the tubes. Collars 442 are slidable on the tube 434 in the portions of the tube below the shoulders 438. The collars 442 are tapered at their bottom end as at 443 for reasons which will be described in detail subsequently. The peripheries of the collars 442 are threaded along the upper portions of the collars to receive retaining rings 444 having a construction corresponding to the rings 440. Washers 446 are positioned on the collars 442 above the retaining rings 444 to hold helical springs 448 in constraint between the washers and the retaining rings 440. The springs 448 are disposed on the tubes 434.

Annular actuators 450 (best seen in Figure 20) are provided with tapped holes such that the actuators can be screwed on the threaded peripheries of the collars 442 to positions abutting the retaining rings 444. The bottom portions of the actuators 450 are provided with enlarged diameters and are hollowed to receive washers 452 made from a suitably resilient material such as rubber. The actuators 450 are inwardly turned at their bottom end to form lip portions 454 for retaining the washers 452 in fixed position within the hollow portions of the actuators. A plurality of holes 456 are provided at spaced intervals in the periphery of the actuators 450 to receive suitable implements such as spanner wrenches for screwing the actuators on the threaded portions of the tubes 442 to positions abutting the retaining rings 444.

Arms 460 extend upwardly from the tops of the tubes 434 to hold valve stems 462 extending through holes in the arms. The valve stems 462 are threaded along their periphery at positions above the arms 460 to receive tapped lock nuts 464. Shoulders 466 are provided on the peripheries of the valve stems 462 at positions below the arms 460 so that the stems can be maintained in fixed positions on the arms between the shoulders 466 and the lock nuts 464. At their lower ends, the valve stems 462 have annular head portions 468 (best seen in Figure 23) tapered at their outer edges at 470 to engage the tapered surfaces 443 at the lower edges of the collars 442. In this way, the collars 442 form valves with their associated head portions 468. The valve stems 462 have a sufficient length to extend above the level of the fluid in the container 426 (best seen in Figure 20) even when a maximum amount of fluid is in the container. The valve stems 462 are tubular, providing air vents 472.

Brackets 474 (Figure 21) are attached as by bolts to the bosses 32 extending upwardly from the flange portion 26 of the housing 24. The brackets 474 support a guide track 476 on which the rollers 312 are disposed. As may be best seen in Figure 22, the guide track 476 has a first portion inclined at a moderate angle and extending annularly through a relatively short angular length. The guide

track 476 also has a second portion which extends in a horizontal direction for a relatively long angular distance from the end of the first portion of the guide track. A third portion of the guide track 476 extends downwardly at a relatively moderate slope and for a relatively short angular distance from the end of the second portion on the guide track.

The feed star 246 is mounted on the sleeve 96 for rotation with the sleeve to control the positioning of the containers 420 on the platform 398. As the feed star 246 rotates, it moves the containers 420 along the platform toward the feed star 320. Because of the synchronization in the movements of the feed stars 246 and 320, the containers 420 become transferred from the pockets in the feed star 246 to the pockets in the feed star 320 in a manner similar to that described for the transfer of containers in the previous embodiments. The transfer of the containers 420 from the pockets in the feed star 246 to the pockets in the feed star 320 is facilitated by the fact that the pedestals 314 become vertically aligned with the platform 398 at the position of transfer of the containers.

As described previously, the pedestals 314 are mounted on the lifters 306, which are in turn slidable on the posts 304. The lifters 306 also carry the rollers 312, which are adapted to roll on the guide track 476. Because of this relationship, the lifters 306 have at any instant a vertical disposition on the posts 304 dependent upon the disposition of the rollers 312 on the guide track 476 at that instant. This causes the lifters 306 to have initially an upward movement for a short period of time, a horizontal disposition for a relatively long period of time and then a downward movement for a short period of time in each revolution of the lifters.

When the lifters 306 move upwardly during each revolution of the lifters, they carry the containers 420 upwardly since the containers are positioned on the pedestals 314. The containers 420 in turn exert an upward force against the actuators 450 by pressing against the resilient washers 452. This causes the actuators 450 to move upwardly against the action of the springs 448 and to carry the collars 442, the retaining rings 444 and the washers 446 upwardly in accordance with their own movements. The upward movement of the actuators 450, the collars 442, the retaining rings 444 and the washers 446 is limited by the shoulders 438 on the tubes 434, as may be best seen in Figure 23.

Upon an upward movement of the collars 442 on the tubes 434, the collars become displaced from the head portions 468 at the bottom of the stem portions 462. This causes passageways 482 (best seen in Figure 23) to be created for the flow of fluent material 478 through the containers 420. The fluent material 478 flows through a circuit including the reservoir 426, the holes 428 in the reservoir and in the plate 424, the tube 434 and the passageways 482. The fluent material 478 continues to flow through the containers 420 during all of the time that the rollers 312 are riding along the horizontal portion of the guide track 476.

Since the mouths of the containers 420 are pressed against the washers 453 during the flow of the fluent material 478 into the containers 420 (best seen in Figure 23), the containers would in effect become sealed. This would prevent air from escaping out of the top of the containers 420 as the fluent material in the reservoir 426 flowed into the cans. Because of this, some other path of escape has to be provided for the air in the containers 420 as the air becomes displaced by the fluent material flowing through the containers. The escape of the air in the containers 420 takes place through the holes 472 in the stem portions 462. The air can escape through the holes 472 in the stem portions 462 since the stem portions are positioned at their upper ends above the level of the fluent material in the reservoir 426 even when the fluent material in the reservoir is at a maximum height.

When the rollers 312 reach the declining portion of the guide track 476 (best seen in Figure 22), the rollers move downwardly and force the pedestals 314 downwardly with them. This causes the containers 420 to move downwardly from their disposition against the actuators 450. Since the containers 420 no longer press upwardly against the actuators 450, the force exerted by the springs 448 against the washers 446 becomes predominant.

- 10 As a result of the force exerted by the springs 448, the actuators 450 move downwardly to the position shown in Figure 24. In the disposition of the members corresponding to that shown in Figure 24, the head portions 468 on the stem portions 462 abut the collars 442 at the 15 bottom of the collars to prevent the flow of the fluent material 478 into the containers. The action of the spool portions 468 and the collars 482 in preventing the flow of the fluent material is aided by the tapered surface 443 on the collars and the tapered surfaces on the head portions. 20 Because of the tapered surfaces, the head portions 468 are able to seat snugly within the collars 482 to prevent the flow of fluent material.

It should be appreciated that the containers 420 are filled on a sequential basis. This may be best seen in 25 Figure 22, which shows all of the containers 420 moving angularly with the feed star 320 at one particular instant. By way of illustration, the container at the extreme left has just been transferred from the feed star 246 to the feed star 320. The second to eighth cans, inclusive, have 30 progressively increasing amounts of fluent material in them when the count is made from the left. The ninth container from the left is completely full and is ready to be removed from the filling station by output means such as an endless conveyor belt.

35 The apparatus described above is advantageous because it can be disposed in certain sub-assemblies which can be easily attached to or detached from the base assembly shown in Figures 1 and 2. For example, a first sub-assembly can include the casing 300, the posts 304, the lifters 306, the rollers 312, the support tube 421, the sleeve 422, the plate 424, the reservoir 426, the collar 442, the actuators 450 and the stem portions 462. A second sub-assembly can include the brackets 474 and the guide track 476.

40 45 When it is desired to use the apparatus shown in Figures 21 to 25, inclusive, and described fully above, the first sub-assembly mentioned in the previous paragraph can be easily attached as by screws to the rim portion 52 of the support member 40. In like manner, 50 the second sub-assembly mentioned in the previous paragraph can be easily attached as by screws to the collar 32 on the flange portion 26 of the housing 24. After the filling operation has been completed, the first and second sub-assemblies can be easily detached from the 55 base assembly shown in Figures 1 and 2 by removing the appropriate screws. The sub-assemblies can then be stored until the next time that a gravity type of filling operation is desired. After the sub-assemblies have been removed from the base assemblies, various other sub- 60 assemblies can be attached to the base assemblies to obtain different types of filling operations.

65 It should be appreciated that the apparatus shown in Figures 21 to 26, inclusive, does not necessarily have to be stored in the form of sub-assemblies. Actually, it may be desirable to retain loose parts or groups of parts and to build the apparatus from these parts. For example, it may be desired to store in disassembled relationship such parts as the posts 304 and the lifters 306 since such parts can be used in the apparatus shown in Figures 70 16 to 20, inclusive, as well as in the apparatus shown in Figures 21 to 26, inclusive. By storing the various parts in their disassembled relationship only a minimum number of parts is needed to build up apparatus for performing various types of filling operations. These types 75 of filling operations can include those specifically dis-

cussed in this application and others not specifically discussed in this application. In this way, only a minimum amount of capital investment is needed to perform a wide variety of different filling operations.

I claim:

1. In a device of the class described provided with guide tracks having particular configurations and means for riding along the guide tracks to control the flow of fluent material from a reservoir sequentially into a plurality of containers guided in their movement by first and second feed stars at least initially along a platform, the combination of casing means, a drive shaft extending through the casing means, a first housing extending upwardly from the casing means in supported relationship to the casing means and having a flange portion at a lower position with bosses extending upwardly from the flanges for supporting the guide tracks at particular positions above the bosses in accordance with the functions of the different guide tracks, a first shaft extending upwardly through the first housing in driven relationship to the drive shaft, a support member mounted on the drive shaft at a position above the first housing and having a bottom rim portion and an intermediate shoulder portion for supporting the reservoir, the second feed star, the containers and the control means for movement of the control means along the guide tracks to obtain a sequential filling of the containers, a second housing extending upwardly from the casing means in supported relationship to the casing means and having a surface at an upper position for supporting the containers during at least the movement of the containers with the first feed star, a second shaft extending upwardly through the second housing in driven relationship to the drive shaft, and a second support member mounted on the second drive shaft at a position above the second housing for holding the first feed star for rotary movement in accordance with the rotation of the shaft and in coupled relationship to the first feed star.

2. In combination with a reservoir for holding fluent material, there being a plurality of ports in the reservoir for the flow of the fluent material from the reservoir into sequentially presented containers, valve means associated with the ports in the reservoir for controlling the flow of the fluent material into the containers in accordance with the disposition of the containers and of the valve means, at least one guide track having a configuration for controlling the disposition of the valve means, a plurality of control means disposed for movement on the guide track and coupled to the valve means to produce variations in the disposition of the valve means in accordance with variations in the disposition of the containers, and means for guiding the movements of the containers in accordance with the rotary movements of the reservoir; the combination of casing means, a drive shaft extending through the casing means, a first housing extending upwardly from the casing means in supported relationship to the casing means, means extending upwardly from the first housing in supported relationship to the housing for holding the guide track at a particular height above the first housing in accordance with the particular type of filling operation being performed, a first shaft extending upwardly through the housing in driven relationship to the drive shaft, a support member mounted on the shaft at a position above the housing and coupled to the housing, the control means and the valve means to produce a movement of the control means on the guide track and a sequential opening and closing of the ports by the valve means in accordance with the movements of the control means on the guide tracks, and means including a second housing supported by the casing means and a second shaft extending through the second housing in driven relationship to the drive shaft for moving the containers to a position for transfer to the guide means controlling the movements of the containers with the reservoir.

3. In combination with a reservoir for holding fluent material, there being a plurality of ports in the reservoir for the flow of the fluent material from the reservoir into sequentially presented containers, valve means associated with the ports in the reservoir for controlling the flow of the fluent material into the containers in accordance with the disposition of the containers and of the valve means, at least one guide track having a configuration for controlling the disposition of the valve means, control means disposed for movement on the cam track and coupled to the valve means to produce variations in the disposition of the valve means in accordance with variations in the disposition of the containers and means for guiding the movements of the containers in accordance with the rotary movements of the reservoir; the combination of casing means, a drive shaft extending through the casing means, a housing having a flange portion for support on the casing means and having a body portion extending upwardly from the flanged portion, a plurality of spaced bosses disposed at the periphery of the flange portion on the housing and having flat upper surfaces for supporting the guide track at a particular height above the bosses dependent upon the type of filling operation being performed, a first shaft extending through the housing in driven relationship to the drive shaft, a support member carried by the driven shaft and having at least a pair of flat surfaces for holding the reservoir, the valve means and the control means for maintaining the control means on the guide track to produce a sequential disposition of the valve means for the filling of the containers, and means including a second housing supported by the casing means and including a second shaft extending through the housing in driven relationship to the drive shaft for advancing the containers to a position for transfer to the guide means associated with the reservoir.

4. In combination with a reservoir for holding fluent material, there being a plurality of ports in the reservoir for the flow of the fluent material from the reservoir into sequentially presented containers, valve means associated with the ports in the reservoir for controlling the flow of the fluent material into the containers in accordance with the disposition of the containers and of the valve means, at least one guide track having a configuration for controlling the disposition of the valve means, control means disposed for movement on the guide track and coupled to the valve means to produce variations in the disposition of the valve means in accordance with variations in the disposition of the containers, and means for guiding the movements of the containers in accordance with the rotary movements of the reservoir; the combination of casing means, a drive shaft extending through the casing means, a housing having a flange portion for support on the casing means and having a body portion extending upwardly from the flange portion, a plurality of spaced bosses disposed at the periphery of the flange portion on the housing and having flat upper surfaces for supporting the guide track at a particular height above the bosses dependent upon the type of filling operation being performed, a first shaft extending through the housing in driven relationship to the drive shaft, a support member carried by the first driven shaft and having a bottom rim portion and an intermediate shoulder, the rim and shoulder portions of the support member having flat and parallel surfaces for holding the reservoir, the control means and the valve means for rotary movement with the support member and the driven shaft and for advancing the control means along the guide track in accordance with such rotary movements to operate the valve means in sequence for the flow of fluent material from the reservoir into the containers, and means including a second housing supported on the casing means and including a second shaft extending through the housing in driven relationship to the drive shaft to advance the containers to a position for the transfer of the

containers to the guide means associated with the reservoir.

5. In combination with a reservoir for holding fluent material, there being a plurality of ports in the reservoir for the flow of the fluent material from the reservoir into sequentially presented containers, valve means associated with the ports in the reservoir for controlling the flow of the fluent material into the containers in accordance with the disposition of the containers and of the valve means, at least one guide track having a configuration for controlling the disposition of the valve means, control means disposed for movement on the guide track and coupled to the valve means to produce variations in the disposition of the valve means in accordance with variations in the disposition of the containers, and means for guiding the movements of the containers in accordance with the rotary movements of the reservoir; the combination of means including first and second feed stars and a platform for guiding the movements of the containers in accordance with the rotary movements of the reservoir, casing means, a drive shaft extending through the casing means, a housing extending upwardly from the casing means in supported relationship to the casing means and having a flat surface at an upper position for holding the support platform, a first shaft extending through the housing in driven relationship to the drive shaft, a sleeve carried by the first driven shaft at a position above the housing and having a flat surface at its upper end for holding the first feed star for rotary movement in accordance with the movements of the shaft, a second housing extending upwardly from the casing means in supported relationship to the casing means and having at spaced positions along its periphery a plurality of flat surfaces for holding the guide track in fixed position for movement of the control means on the track, a second shaft extending through the second housing in driven relationship to the drive shaft, and a sleeve carried by the second driven shaft at a position above the second housing and having a pair of parallel flat surfaces for holding the second feed star in position to obtain a transfer of the containers from the first feed star to the second feed star during the rotary movement of the sleeve and for holding the reservoir, the valve means and the containers to sequentially operate the valve means for the flow of the fluent material into the containers upon the transfer of the containers to the second feed star and in accordance with the movements of the control means on the guide track during the rotary movement of the sleeve.

6. In combination with a reservoir for holding fluent material, there being a plurality of ports in the reservoir for the flow of the fluent material from the reservoir into sequentially presented containers, valve means associated with the ports in the reservoir for controlling the flow of the fluent material into the containers in accordance with the disposition of the containers and of the valve means, means for holding the containers for an angular movement in a horizontal plane, guide track means for controlling the relative disposition of the containers and the reservoir in the vertical direction for filling operations with movements in this direction and for controlling at the same time the operation of the valve means, means including control means disposed for movement on the guide track means and coupled to the valve means to produce a controlled operation of the valve means in accordance with the movements of the control means and coupled to the container-holding means for producing vertical movements of the containers for filling operations with movements in this direction, and means for guiding the containers into angular paths of movement in accordance with the rotary movements of the reservoir; the combination of casing means, a drive shaft extending through the casing means, a first housing supported by the casing means at a position above the casing means and having bosses disposed at spaced peripheral

positions on the housing and surfaces on the bosses for supporting the guide track means at particular heights above the bosses, a first shaft extending through the housing in driven relationship to the drive shaft, a support member carried by the first driven shaft and having first and second support surfaces for holding the reservoir and the control means for movement on the guide track means and for holding the means for controlling the angular movements of the container-holding means in a horizontal plane with or without vertical components and for holding the valve means for producing the flow of the fluent material into the containers, and means including a second housing supported by the casing means at a position above the casing means and including a second shaft extending through the housing in driven relationship to the drive shaft for moving the containers into position for transfer to the guide means associated with the reservoir.

7. In combination with a reservoir for holding fluent material, there being a plurality of ports in the reservoir for the flow of the fluent material from the reservoir into sequentially presented containers, valve means associated with the ports in the reservoir for controlling the flow of the fluent material into the containers in accordance with the disposition of the containers and of the valve means, means for holding the containers either for an angular movement in a horizontal plane having no vertical components or in a horizontal plane having vertical components relative to the valve means, guide track means for controlling the relative disposition of the containers and the reservoir in the vertical direction for filling operations with movements in this direction and for controlling at the same time the operation of the valve means, means including control means disposed for movement on the guide track means and coupled to the valve means to produce a controlled operation of the valve means in accordance with the movements of the control means and coupled to the container-holding means for producing vertical movements of the containers for filling operations with movements in this direction, and means for guiding the containers into angular paths of movement in accordance with the rotary movements of the reservoir; the combination of casing means, a drive shaft extending through the casing means, a first housing extending upwardly from the casing means in supported relationship to the casing means and having a flange portion and bosses extending upwardly from the flange portion with flat upper surfaces for supporting the guide track means, a first shaft extending through the first housing in driven relationship to the drive shaft, support means carried by the first driven shaft at a position above the first housing and having first and second flat surfaces for supporting the reservoir and the containers and the valve means for rotary movement of these members and for rotary movement of the containers relative to the valve means in a horizontal plane or in a horizontal plane having vertical components dependent upon the type of filling operation being performed to produce a filling of the containers during such rotary movements, a second housing extending upwardly from the casing means in supported relationship to the casing means and having a flat surface for supporting the containers during their guided movement to a position of transfer for rotary movements of the reservoir, a second shaft extending through the second housing in driven relationship to the drive shaft, and a sleeve carried by the second shaft at a position above the second housing to carry the guide means for movement of the containers to the position of transfer for rotary movements with the reservoir.

8. In combination, a first housing, a platform supported by the housing structure for holding a plurality of containers for movement as by a conveyor along the platform, a first shaft supported by the housing for rotation relative to the housing, means supported by the

shaft for providing a first shoulder for maintaining, at a particular distance from the platform, conveying means for leading the containers along the platform to a transfer position, a second housing, a second shaft supported by the second housing for rotation relative to the housing, means supported by the second shaft for providing a second shoulder for maintaining, at a particular distance from the platform, conveying means for receiving the containers at the transfer position and for positioning the containers for the filling of the containers, and means supported by the second shaft for providing a third shoulder for carrying the means for filling the containers.

9. In combination in container-filling apparatus including a reservoir for holding fluent material and at least a first port in the reservoir and including a compartment contiguous to the port for the flow of the fluent material from the reservoir through the port and into the compartment and including at least a second port in the compartment for the flow of the fluent material from the compartment through the second port and into a container and including a cover plate in the reservoir at a position removed from the first port and an orifice in the cover plate, a valve stem movable through the ports in the reservoir and in the compartment and having a guide portion at a position contiguous to the orifice in the cover plate and at least one spool portion at a position contiguous to the ports in the reservoir and the compartment for a snug fit within the port in the reservoir to provide for an opening of the port in the reservoir and a closing of the port in the compartment in one axial positioning of the valve stem for a flow of the fluent material from the reservoir into the compartment and to provide for a closing of the port in the reservoir and an opening of the port in the compartment in a second axial positioning of the valve stem for a flow of the fluent material from the compartment into the container, the valve stem being notched at the end near the port in the reservoir to provide a regulated opening and closing of the port in the reservoir in accordance with the movements of the piston.

10. In combination in container-filling apparatus including a reservoir for holding fluent material and at least a first port in the reservoir and including a compartment contiguous to the port for the flow of the fluent material from the reservoir through the port and into the compartment and including at least a second port in the compartment for the flow of the fluent material and from the compartment through the second port and into a container and including a cover plate in the reservoir at a position removed from the first port and an orifice in the cover plate, the combination of a valve stem movable through the ports in the reservoir and in the compartment and having a guide portion at a position for movement in the orifice in the cover plate and including at least one spool portion for movement to a first position relative to the ports in the reservoir and the compartment for providing for a closure of the port in the compartment and an opening of the port in the reservoir and movable to a second position relative to the ports in the reservoir and in the compartment for providing for an opening of the port in the compartment and a closure of the port in the reservoir, guide track means having a guide surface of particular configuration, control means movable on the guide surface of the guide track means, a drive rod connected at one end to the control means and pivotable relative to the reservoir cover at the other end and coupled at an intermediate position to the guide portion of the valve stem to produce a movement of the valve stem toward or away from the ports in accordance with the movements of the control means on the guide track means.

11. In combination in container filling apparatus, including a reservoir for holding fluent material and at least a first port in the reservoir and including a compartment contiguous to the port for the flow of the fluent

material from the reservoir through the port and into the compartment and including at least a second port in the compartment for the flow of the fluent material from the compartment through the second port and into a container and including a cover plate in the reservoir at a position removed from the first port and an orifice in the cover plate, a valve stem movable through the ports in the reservoir and in the compartment and having a guide portion at a position for movement in the orifice in the cover plate and including at least one spool portion for movement to a first position relative to the ports in the reservoir and the compartment for providing for a closure of the port in the compartment and an opening of the port in the reservoir and movable to a second position relative to the ports in the reservoir and in the compartment for providing for an opening of the port in the compartment and a closure of the port in the reservoir, means including control means coupled to the guide portion of the valve stem and drive means coupled to the control means and the valve stem in removable relationship to the valve stem for providing a movement of the valve stem in a direction toward or away from the orifice in accordance with the movements of the control means, and guide track means for guiding the movements of the control means to obtain proper movements of the valve stem.

12. A can filling apparatus comprising a reservoir for holding fluent material having a port located in a bottom wall thereof, a compartment disposed at least in part beneath said reservoir and contiguous to said port and in communication therewith, said compartment having a second port therein located directly beneath and in axial alignment with said first mentioned port adapted to permit the flow of said fluent material from said compartment into a container, a valve stem movable through said ports and said reservoir, and a spool portion carried on one end of said valve stem co-acting alternately within each of said ports for opening and closing said ports, said spool portion having means thereon to gradually close said first mentioned port.

13. A can filling apparatus comprising a reservoir for holding fluent material having a port opening downwardly from the bottom of said reservoir, a compartment disposed at least in part directly beneath said reservoir and contiguous to said port and in communication therewith, said compartment having a second port therein in axial alignment with said first mentioned port, an elongated sleeve in communication with said compartment having a second port therein in axial alignment with said first mentioned port adapted to permit the flow of said fluent material from said compartment through said sleeve into a container, a valve stem movable through said ports and said reservoir, a spool portion carried on said valve stem intermediate the ends thereof and positioned for sliding engagement into said first mentioned port, and a second spool portion carried on the end of said valve stem co-acting with said second port to slidably close said second port.

14. A container filling apparatus comprising a first housing, a drive shaft, a first driven shaft extending longitudinally through said first housing and driven by said drive shaft, a support plate mounted on said housing for receiving unfilled containers, means carried by said first driven shaft for moving empty containers along said support plate to a transfer position, a second housing, a second driven shaft extending longitudinally through said second housing, means mounted upon the second shaft for receiving the containers at the transfer position and for advancing the containers to filling positions, filling means, means mounted on the second housing for actuation of the filling means at particular positions during the advance of the containers with fluent material, a casing mounted on said second shaft and rotatable therewith, and a cam track mounted on said second housing for moving the containers to and from the filling means in timed relation to

the filling operation whereby said containers are filled from the bottom.

15. In combination in container-filling apparatus including a reservoir for holding fluent material and at least a first port in the reservoir and including a compartment contiguous to the port for the flow of the fluent material from the reservoir through the port and into the compartment and including at least a second port in the compartment for the flow of the fluent material from the compartment through the second port and into a container and including a cover plate in the reservoir at a position removed from the first port and an orifice in the cover plate, the combination of a valve stem movable through the ports in the reservoir and in the compartment and having a guide portion at a position for movement in the orifice in the cover plate and including at least one spool portion for movement to a first position relative to the ports in the reservoir and the compartment for providing for a closure of the port in the compartment and an opening of the port in the reservoir and movable to a second position relative to the ports in the reservoir and in the compartment for providing for an opening of the port in the compartment and a closure of the port in the reservoir, guide track means having a guide surface of particular configuration, control means movable on the guide surface of the guide track means, a drive rod connected at one end to the control means and pivotable relative to the reservoir cover at the other end and coupled at an intermediate position to the guide portion of the valve stem to produce a movement of the valve stem toward or away from the ports in accordance with the movements of the control means on the guide track means.

16. A container filling apparatus comprising a first housing, a drive shaft, a first driven shaft extending longitudinally through said first housing and driven by said drive shaft, a support mounted on said drive shaft, a reservoir mounted on said support, cylinders carried by said reser-

voir and mounted externally thereof, a bracket mounted on said support, pistons in said cylinders, a cam track carried by said bracket and extending circumferentially of said reservoir and cylinders, means carried by said pistons co-acting with said cam track for actuation of said pistons in timed relation with the rotation of said reservoir and adjustable means in said cam track for varying the throw of said pistons to permit adjustment of the amount of fluid drawn in and ejected from said cylinders.

10 17. A container filling apparatus comprising a housing, a driven shaft extending longitudinally through said housing, a support plate mounted on said driven shaft, a reservoir mounted on said support plate and rotatable therewith, filling means carried by said reservoir, said filling means comprising a port in said reservoir, a tube projecting outwardly from said port, a slidable collar on said tube, a valve co-acting with said slidable collar, a stem rigidly secured to said tube having a vent extend longitudinally through said stem and valve, means urging said sleeve against said valve to close said tube and sleeve, a casing mounted on said support means and rotatable therewith, means for supporting containers on said casing, a cam track mounted on said housing and co-acting with said container supporting means to urge said containers against said sleeve to cause the sleeve to open said valve and permit a fluent material to flow from said reservoir into said container in timed relation to the movement of said reservoir.
